SCREW THREAD TESTER

Frank Short, Canton Center, Conn.

Application December 26, 1945, Serial No. 637,295

12 Claims. (Cl. 33—199)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a machine for testing threads, both internal and external. In the mechanic arts it is important, and in some situations of the utmost importance, that the threads of the parts to be tested be free from imperfections or irregularities such, for instance, as eccentricity to the axis of the part, or defect in pitch, or any of a number of imperfections that occur in the fabrication of threads. The machine about to be described is designed to detect the slightest imperfections and/or inaccuracies of the threads, and visually indicate their nature, character or extent, to the operator upon suitable indicator devices wherefrom he may use his judgment as to whether the workpiece will be rejected or retained.

Two novel principles are involved in the operation of the machine, one applying to external threads and the other to internal threads. For testing external threads, the invention contemplates the provision of an exact duplicate or pattern of the perfect thread, but of opposite hand from the thread to be gaged, and rolling this opposite hand thread in engagement with the thread to be gaged. The result of such action, if the thread to be gaged is perfect, will be no movement of the indicators, whose operation will be caused by imperfections or irregularities of some sort, and in no other way.

For internal threads, a fractional size of a perfect thread is employed and placed in engagement with the thread being tested, but in this case the threads are of the same hand as those to be tested, and the pattern or perfect gage will have a pitch diameter a predetermined fraction of that of the thread to be tested, in order that the gage or pattern thread may be moved into and out of contact with the thread being tested.

In the drawings:

Figure 1 is a top plan view, somewhat schematic, of a machine for gaging both external and internal threads, including a partly broken away shell or workpiece suitable for illustration purposes;

Figure 2 is a vertical section about on line 2—2 of Figure 1 looking in the direction of the arrows;

Figure 2a is a fragmentary detail section on line 2a—2a of Figure 1;

Figure 3 is a top plan view of a modification including a fragment of the workpiece and showing

the mechanism for engaging an external thread;

Figure 3a is an end elevation of the parts between the arrows 3a—3a of Figure 3, looking in the direction of the arrows;

Figure 4 is a vertical section of Figure 3 about on line 4—4 of Figure 3;

Figure 4a is a wiring diagram appropriate to the operations of the mechanism shown in Figures 3 and 4;

Figure 5 is a side elevation of another modification showing a mechanism for gaging an internal thread;

Figure 6 is an elevation partly in section of modified means for rotating the workpieces, to compensate for differences in outside diameter of the workpiece;

Figure 7 is a chart showing several indications of typical errors.

Referring to the drawings, and particularly Figures 1 and 2, the numeral 1 designates the base of the machine shown broken away for economy in space. This will be properly supported above a suitable support upon legs 2, Fig. 2.

Numeral 3 designates a workpiece, in this case 25 a shell, cylindrical for the most part, and provided with external threads 4 at one end and internal threads 5 at the other. These threads are the ones to be tested or gaged for imperfections of shape or location, or both, obviously for the purpose of ascertaining whether they will coact properly and accurately with the threads of the other element to which the workpiece is to be threadedly united.

The shell or workpiece is mounted for true 35 horizontal rotation upon its axis upon four rollers 6 mounted upon shafts journaled in brackets secured to the base as shown in Figure 2.

A motor 7 and a gear reducer 8 are provided to give a slow rotation to the shell. These may be of any conventional type, and are mounted on the upper end of a web 8' whose lower end is fastened to the base 1 by screws or other suitable means.

The reducer is provided with an inner sleeve 8", and an outer sleeve 9 in which the slow speed shaft 10 is journaled. A collar 11 is provided on the outer end of the shaft and a gear wheel 12 provided with a boss 13 is mounted on the inner end of the shaft. The collar 11 and gear 12 are secured to the shaft by set screws, the mounting being such that end-wise movement of the shaft is prevented.

A permanent magnet 12' is secured to the boss 55 13, of gear wheel 12, against which the shell or

workpiece may be placed to rotate the shell at a desired slow speed without slippage.

Pivoted at 15 to a plate on the base 1 is an arm 16 whose upper end is provided with a bearing member 17 for a shaft 18 whose other end has a bearing in an elongated gage member 19, fixed to an arm 16' (Figure 2a), pivoted at 16'' to the base in the same manner as arm 16. By this means, the shaft 18 may be moved in an arcuate path parallel to itself about the axis defined by aligned bearings 15 and 16''. The member 19 has secured to one side a gage 20 having a pointer 20' thereon, and a slideable spring backed contact finger 21. The opposite side of the dial member is provided with a lateral extension which has a smooth machined face 22 for contact with the slideable finger 23 of another gage 24, similar to the gage 20. Gage 24 has a pointer 24'. The arm 16 has a lateral extension 25 positioned somewhat above the base 1, and having an aperture therethrough for the passage of a bolt 26 having a head 27, which serves as a stop to limit the counterclockwise rocking movement of the arm 16 as viewed at Figure 2. Interposed between this extension 25 and the base 1 is a compression spring 28, tending to rock the arm 16, and consequently the shaft 18 and dial member away from the slideable finger 23 of the gage 24, mounted on a pedestal 29 secured at its lower end to the base 1.

Slidably mounted on the shaft 18 is the gaging or testing wheel 30 formed with an integral sleeve 31 to more effectually guide the wheel in its longitudinal movements on the shaft, if there should be in the testing operation occasion for such movements. This gaging wheel is urged by spring 28 into frictional engagement with the external threads 4 of the shell or workpiece 3 as clearly shown in Figure 1, and its threads are of opposite hand from the threads 4. The slideable finger 21 of the gage 20 is in engagement with the outer smooth face of the gage wheel 30, which face lies in a plane normal to the axis of shaft 18 so that its movement along the shaft 18, if there is any, during the rotation of the shell, will actuate the finger and consequently its pointer. The wheel 30 turns with the external thread 4, but in opposite direction, and as intimated, if the gaged or tested threads are accurate and in accordance with requirements, there will be no movement of the pointer of gage 20, but if the thread 4 should be eccentric to the axis of the shell, an inward and outward movement will be imparted to the shaft 18 in parallelism with itself, and consequently there will be a back and forth movement of the pointer of the gage 24, which movement, it will be understood, will be amplified to an extent to be clearly visible to the operator and thereby inform him of the inaccuracy of the thread. Now if the pitch diameter of the thread 4 is greater or less than that specified, there will be a slow longitudinal movement of the wheel 30 on the shaft 18, and the pointer of the gage 20 will indicate the imperfection, so also will an inaccurate lead of thread 4 be indicated. Should the thread engaged have an angularity with regard to the axis of the workpiece, a back and forth movement of the wheel 30, and consequently the shaft 18, will result, and the imperfection will be indicated on the gage 24. A combination of errors in the thread 4 will be indicated by a combination of movements of the dial indicators of both gages 20 and 24.

The mechanism so far described gages or tests

external threads, and may be used for that purpose with or without the internal thread gaging mechanism to be described.

The bolt 26, Figure 2, extends through an aperture in the base 1, where below the base it is secured to the outer end of a diagonally extending lever 31 fulcrumed upon a bar 32 mounted in ears 33 depending from the underside of the base. The reason for the lever and its closely associated parts will become apparent later on. A bolt 34 passes through an opening in the inner end of the lever and is held thereto by a nut, the bolt extending upwardly through an opening in the base and through an opening in an extension 35 integral with and extending laterally from an arm 36, corresponding to the arm 16. This arm 36 is pivoted at 37 to a plate secured to the base. The bolt 34 is reduced in diameter to form a shoulder below the extension 35 and carries a washer 38, between which and the extension there is a spring 38'. A cotter pin (not shown) passes through the reduced end of bolt 34 to maintain the washer in position. Rigidly secured to the upper end of the arm 36 is an elongated bearing member 39 in which there is non-rotatably mounted the horizontal shaft 39' upon which the gage wheel 41 and its hub 40 are slideable and which functions to test the accuracy of the internal threads 5 in the shell or workpiece 3. This bearing member, like the gage member 19, has a lateral extension 43 with a smooth machined face 44 for engagement with the finger 45 of the gage 46 which carries the pointer 46'. This gage is mounted on a pedestal 47 on the base 1, as shown in Figure 2. Spring 38 surrounds headed bolt 34, and being interposed between extension 35 and washer 38' tends to rock arm 36 and consequently bearing member 39 toward the gage 46, and threads 41 into contact with threads 5 so that rocking movement of the arm 36, due to an irregularity or imperfection in the internal thread 5 in the shell 3 sensed by the gaging threads 41, will be imparted to the gage 46 and there indicated by a movement of the pointer 46'. Should it be, for instance, that the workpiece thread is eccentric to the axis of the workpiece, the movement of the arm 36 will be inward and outward with respect to the axis of the shell, the movement of the arm 36 being precisely like that of the arm 16 which functions in connection with testing the external threads as heretofore described.

The gage wheel 41 having threads, say exactly nine-tenths of the correct pitch diameter of that of the workpiece thread 5, is mounted on the shaft 39' in such manner that it is free to slide axially thereon and also to move laterally parallel to itself, through the instrumentality of the spring-urged arm 36.

A normal thread 5, when the workpiece is rotated, will cause a continuous axial movement of the gage wheel 41. This axial movement of the gage thread is compensated by the mechanism now to be described. Integral with the hub 40 of the gage wheel 41 is an annular member 48 having side flanges 49 between which is an annular groove 50 which receives the ball 51 on the end of arm 52 of a lever 53 pivoted at 54 to a block 55 slidably mounted in a frame 56 mounted upon a pedestal 57 whose lower end is secured to the base 1. Mounted on the frame 56 is a gage 58 having a pointer 58', and a finger or contact element 59 adapted to engage the block, there being springs 60 which urge the block away from the dial and toward a stop 61 in the frame, against

which stop the block rests when not actively engaged in its work. The other arm 62 of the lever 53 is traversed by a pin 63 which extends through elongated slots 64 in ears 64' integral with a longitudinal movable semicylindrical member 65. The member 65 has a smooth, unthreaded interior or concave surface and is held in place against threads 71' or shaft 72 in any suitable manner such as by being splined on shaft 67 fixed in standard 66 and aided to some extent, by rod 19. A second semicylindrical member 68 having internal threads, is pivoted on shaft 67 for sliding thereon as a unit with member 65. Member 68 is provided with a lateral extension 69. Figure 2, adjacent its pivot, which extension 18 forms a seat for a tension spring 70 interposed between the extension and an ear on the stationary member 65 and tending to urge member 68 away from member 65, that is, away from threaded engagement with shaft 72. The member 68 is, as best shown in Figure 1, internally threaded as at 71 and coacts at times with the threads 71' of horizontal shaft 72 mounted rotatably in bearing 73 on standard 66 and at its other end in bearing 74 formed at the upper end of a standard 75 similar to the standard 66, both standards being securely fastened to a base plate 76 secured to base 1. The standard 75 is indicated in dotted lines in Figure 1, and needs no further illustration, it being understood that the only requirements are to support the shaft 72 a suitable distance above the base 1.

Fast to the shaft 72 is a gear wheel 77 in mesh with the gear wheel 72' driven by the motor 7 through the reducer 8. A lateral extension 78 is formed on the bearing 73 and through this and through an ear 69' on the member 65 is passed the headed limiting rod 19, and interposed between the ear and extension, and surrounding the rod is a spring 79 which urges the "sleeve" formed by the members 65 and 68 toward the end of the shaft 72, the head on the rod 79 limiting the outward movement of the sleeve by engagement between the said head and the extension 78. To the bearing 73 is pivoted at 71 a lever 80 having a widened portion 81 for sliding engagement with the threaded member 68 to, at appropriate times, move said member over and against the threads 71' of the shaft 72 against the action of spring 70 to cause movement of the sleeve on the shaft when the shaft is rotated, thereby to rock the lever 53 so that the block will operate the finger 59 of gage 58 to indicate the longitudinal fluctuations of the gaging wheel 41. The lever 80 has a narrow handle 82 adapted to enter one or the other of two shallow notches 83 in the head 84 of a standard 86 mounted on the base 1 to hold member 68 in or out of engagement with the threads of shaft 72 as desired.

In the position shown the threaded member 68 is out of engagement with the threads 71' and shaft 72, and consequently the "sleeve" will not be moved by the rotation of the shaft, but during the gaging operation these threads will be in engagement and the sleeve will move longitudinally on the shaft at a rate calculated to compensate for the normal outward travel of the gaging wheel 41 when the thread 5 of the workpiece is of correct dimensions. The movement of the sleeve is determined by the careful calculation of the pitch of the thread on the shaft 72 and the pitch diameters of gear wheels 12 and 77. When the sleeve has reached the limit of its predetermined movement, the member 68 will be forced by spring 70 to open position into recess 80' behind a shoul-

der 80" of the lever 80 with the block 55 against the stop 61.

The numeral 87 indicates a plunger having an operating head 87'. A boss 88 on the base has an opening therethrough for the plunger which plunger also passes through an opening in the base 1 with its lower end in position to engage the lever 31' to depress one end of the lever against the influence of the spring 28 and to simultaneously raise the other end and release the tension of the spring 38, this operation being for the purpose of rocking and holding the gaging wheel 30 away from the shell or workpiece and also the gage wheel 41 away from the internal thread 5 of the work to permit withdrawal or insertion of the shell, as may be required. The boss 88 is provided with a bayonet slot 89 coaxing with a cross-pin 90 to hold the plunger in raised or lowered position as desired.

The operation of the mechanism thus far described has been indicated to some extent as the description proceeded, but at the risk of repetition, and for the sake of clarity, it is summarized. The gaging wheel 30 turns with thread 4 but in opposite direction. If the desired factors of the gaged thread 4 are in accordance with the requirement, there will be no movement of the indicators 20' and 24'. If the thread 4 is eccentric with respect to the axis of the work or shell 3, shaft 18 will be rocked or oscillated, in parallelism with itself, with respect to the axis of the shell and an amplified oscillatory movement of the pointer 24' of dial 24 will occur. If the pitch of the thread 4 is greater than or less than specified, there will be a slow longitudinal movement in one direction or the other of the wheel 30 on the shaft which will be shown by the pointer 20' of the gage 20. So also will a faulty lead of thread 4 be shown. A gaged thread having angularity of its axis will cause a back and forth movement of the wheel 30, which will be shown on gage 20. Should there be a plurality of errors they will be indicated by a combination of movements of the pointers of both gages.

For gaging operations of the internal threads, the gaging wheel 41 is placed at the inner end of the thread 5 in the shell and the narrow end of lever 80 is moved over into inner notch 83 of the head 84, closing the member 68 against the threads of shaft 72 and holding it in such engagement. The rotation of the shell 3 will now cause gage wheel 41 to move slowly outwardly moving the sleeve formed by the members 65 and 68 inwardly at the same rate so that there is no movement of the pointer 58' of the gage 58, providing the thread 5 is correct. If the shell thread has an incorrect lead, the pointer 58' will indicate the fault by a continuous lateral displacement. If the axis of thread 5 is angular with respect to the axis of the shell, the pointer 46' will show it by an oscillating movement. If the thread 5 is eccentric to the center line of the shell, the pointer 46' will show it also by an oscillating movement of the pointer.

Modification Figures 3 and 4.—Extending across the base 88 from one side to the other, is a shaft 89' (Figure 4) mounted in oppositely disposed ears 90'. A vertically disposed arm 91 is rockably mounted on one end of the shaft 89' and is provided with a bearing or gage member 100 at its upper end for one end of the gage wheel shaft 93 whose opposite end is mounted in a bearing 94 at the upper end of an arm 95 integrally united with arm 91, and whose lower end is pivoted on the shaft 89' so that the shaft 93 is

supported in true horizontal position. In this form the gage wheel 30 is provided with an elongated pinion 95 which meshes with an idler gear 97 mounted on one end of a shaft 98 carried by the arm 99 of gage member 100, in which the shaft is mounted and secured, as for instance, by set screw 101. The shaft 98 is fixed in member 100 by set screw 102 and carries a gage 103 provided with finger 104 in engagement with the side of the gage wheel 30, and with a pointer 105. The outer end of the gage member 100 has a smooth machined face engaged by the finger 105 of a gage 106 having a pointer 106', and mounted on the upper end of a standard or pedestal 107 secured to the base 88'.

The arm 91 has two lateral extensions integral therewith, one 108, at the left, and the other 109, at the right as seen at Figure 4. A spring 110 connected to the underside of extension 109 and to the base tends to pull the extension 109 over against an adjusting screw 111 in an internally threaded post 112 on the base to thus move wheel 30 away from threads 4. The extension 108 is attached to the armature of solenoid 108' which when energized overcomes the spring 110 and holds the wheel 30 against the thread 4 so that the threads of said wheel will properly engage those of the work. Suitably supported by attachment to a collar 150 fixed to a sleeve 151 of gage 103 is another solenoid 113 whose armature 113' is positioned to engage the finger 104 of the gage 103 under the influence of spring 114. When the solenoid 113 is energized, the armature is pulled away from the finger 104 so that it may function in the usual manner to indicate the longitudinal movement of the gage wheel 30 along its shaft 93 during the gaging operation. When solenoid 113 is de-energized, armature 113' is urged by spring 114 into frictional engagement with contact or finger 104 to thereby hold the latter in any position to which it may be moved. Thus, at the completion of a gaging operation, wheel 30 is moved out of contact with threads 4 by pivoting its shaft 93 about the axis of shaft 89'. The wheel is then moved to its initial position to the right as viewed in Figure 3. This movement also moves finger 104 to the right and because of the action of spring 114 and armature 113', the spring-pressed finger is restrained from moving wheel 30 to the left until such time as solenoid 113 is again energized. A solenoid arrangement like that just described may be employed in connection with the finger 105 of dial 106.

The supply of electric current to the solenoids 108' and 113 is controlled by a switch 115 mounted on extension 109 of arm 91, and carrying contact buttons 116 and 117 engageable by a pin 118, carried by the idler wheel 97. The ratio between the number of teeth on the pinion and those on the idler is such that a given number of turns will be accomplished by the gage wheel 30 between the time the idler pin 118 presses against the button 116 and the time it engages the button 117. Obviously the pin 118 may be adjustable or added pins may be employed to control at will the number of turns of the gage wheel, and a number of turns below the maximum.

As may be seen upon Figure 4a, solenoids 108' and 113 are connected in series with a battery 152 and a switch 115. This switch has buttons 116 and 117 which, when in the position shown, close the circuit. However, pressure upon either button acts to open the circuit through solenoids

108' and 113 whereby to render springs 110 and 114 effective. At the start of a testing operation, gear 97 is in position such that its pin 118 is in contact with button 116, and the circuit is accordingly open. Spring 110 thus acts to hold wheel 30 out of contact with the threads of a workpiece on supporting rollers 6 while armature 113' acts to hold finger 104 in retracted position. The workpiece is now rotated and, as pin 118 moves away from button 116, the latter moves outwardly to close the solenoid circuit. Energization of solenoid 108' moves wheel 30 into engagement with threads 4 while energization of solenoid 113 withdraws armature 113' and permits finger 104 to move into engagement with the face of wheel 30. After a predetermined number of rotations of the workpiece and wheel 30, pin 118 engages button 117 and opens the circuit. During the rotation of the workpiece, the gages 103 and 106 operate in the manner described for gages 20 and 24, Figure 1. The rotation of workpiece 3 is stopped as soon as button 117 is pressed inwardly, spring 110 now acts to move wheel 30 out of engagement with threads 4 while spring 114 acts to yieldingly fix finger or feeler 104 in position. The workpiece is removed, wheel 30 slid to the right, Figure 3, to initial position. This movement also moves finger 104 to retracted position in which position it is now held by armature 113' and spring 114. Switch 153 is opened, idler gear 97 is rotated to bring pin 118 into initial position wherein it holds button 116 depressed, a new workpiece is placed, switch 153 is closed, and the cycle just described is repeated.

In the wiring diagram, Figure 4a, coils are shown corresponding to the solenoids 108' and 113. As stated, another solenoid, like 113, may be included in the circuit with its armature engaging the finger 105 of the dial shown in Figure 3, all of the solenoids being energized and deenergized simultaneously by the closing or opening of switches 115 and 153, as previously described.

Modification Figure 5.—In this modification an arrangement is shown for testing an internal thread. There is a suitable base 119 upon which standard 121 may be secured and provided with roller bearings 6' at its upper end suitably spaced to bear evenly upon and support the shell 3, which in this case is supported a substantial distance above the base. A shaft 122 is rotatable in bearings 123 and 123' on standards 124 and 125 secured to or resting upon the base 119. The shaft extends beyond the bearing 123 and has an additional support in the bearing portion 126 on standard 127 fixed to the base. There is a gage 128 on the upper end of this standard, which gage is a duplicate of the others that have been heretofore described. It has a contact finger indicated in dotted lines, which in this form engages the smooth machined face 129 of a gage member 130 formed at the upper end of arm 131, the lower end of the arm having an integral hub 132 journaled upon the shaft 122. The gage member 130 which is mounted on the arm 131, and virtually a part of it, carries a gage 133 whose finger 134 engages the smooth side of a gear wheel 134' rotatably mounted on a stud shaft 135 carried by the gage member portion of the rockable arm 131. The hub 135' of gear wheel 134' carries the gage wheel 41 in engagement (during the testing operation) with the internal threads 5 of the shell or workpiece 3.

Mounted on the shaft 122 and rotating with it, is a gear wheel 136 having a broad face so that gear 134' may have ample movement axially of shaft 135 while remaining in mesh with gear 136. At the other end of the shaft 122 and beyond the bearing 123' is a gear 137, also fast to the shaft and meshing with a gear 138 of the same size and mounted upon the shaft of the reducer 139 mounted upon a pedestal 140, or upon any other suitable support, maintaining it at the proper elevation relative to the other mechanism.

The arm 131 may be biased toward the gage 128 by a spring 141 secured to an ear 150 on the hub 132 and to an eye 151 on the base 119, or by other suitable means, the requisite being that lateral fluctuations of the arm will be indicated on the dial 128. In this form the thread engaging member 41 may be nine-tenths of the correct pitch diameter of the workpiece threads and is positively driven at the same angular speed as shell 3 so as to have some slippage with respect to the thread 5. The arrangement preferably is such that the gear wheel 138 drives the gear wheel 137 at a one-to-one ratio, and the broad face gear 136 drives the gear wheel 134' also at a one-to-one ratio, thus causing slippage between the gage wheel 41 and the internal threads 5. By this arrangement the angular relation of the threads 5 of the workpiece and those of the gaging wheel will remain constant rather than their lineal relations. So that the angular relation between the threads be not disturbed, I prefer to mount the arm 131 carrying stud shaft 135 on which is mounted the gage wheel 41 and its hub and gear wheel 134', so that there will be no change in pitch diameter relationship between the gears 134' and 136. The gage 133 mounted on the gage member 130, which member is or may be a part of the arm 131, will measure the axial movement of the gear 134', and the gage 128 mounted on fixed standard 127, will measure lateral movement of the arm 131.

Slight differences in outside diameter of the shell or workpiece will affect the axis of rotation of the workpiece. To compensate for this I make the connection between the magnet 141 (Figure 5) and gear 138 (Figure 5) somewhat different as will appear from Figure 6. In this form the magnet 141 which engages the end face 4 of the workpiece is provided with the hollow hub 142 of much larger internal diameter than the reducer shaft 143 to which the gear wheel 138 is fast. The magnet is mounted on the shaft by a plurality of rings 144, two in the present instance, of resilient material, and the hub 142 of the magnet and hub 146 of the gear wheel 138, are each provided with intermeshing clutch teeth 148 between which there is some play, which with the yielding rings produces a positive drive with enough flexibility, to compensate for slight offset of the axis of the workpiece with respect to the axis of the shaft 143.

In Figure 7 is shown a chart showing several indications of typical errors. The curves are plotted for time in revolutions indicated by characters 0-5 at the top of the chart, for the abscissae and pointer positions as ordinates. The movement of the pointer of the dial 24 is shown in solid lines, the movements indicated by the pointer of dial 20, being indicated in dotted lines. The combination of movements of the two indicators referred to give distinctive indications of the several errors to be found, and the accumulations of errors in five or any desired number of revolutions may be seen at a point of

stoppage of the machine. "Limit" at the right of the chart and the ditto marks below it and the space within the brackets shown, may be the permissible limits within which a workpiece is acceptable, thus graphically showing the value of the part under test.

I claim:

1. In a machine for testing the threads of a threaded workpiece for detection of imperfections in the threads of the workpiece, means for supporting the workpiece for true rotation upon its axis, means for rotating the workpiece, a gage wheel having perfect threads, the counterpart of which is desired in the threads of the workpiece and engaging the threads of the workpiece, pivoted means mounting the gage wheel for lateral movement relative to the axis of the workpiece, means mounting said wheel on said pivotal means for rotation and axial movement thereon, means associated with said pivoted means for normally urging the gage wheel into engagement with the threads of the workpiece, means carried by said pivotal means mounting and in engagement with said gage wheel to visually indicate axial movement of said wheel, and means fixedly mounted adjacent and engaging said pivoted means for visually indicating the lateral movements of said gage wheel in response to the movement of said pivoted means imparted by the gage wheel.
2. In a machine for testing the threads of a threaded workpiece for detection of imperfections in the threads of the workpiece, means for supporting the workpiece for true rotation upon its axis, means for rotating the workpiece, a gage wheel having perfect threads the counterpart of which is desired on the threads of the workpiece and engaging the threads of the workpiece and rotated by said workpiece, pivoted means mounting the gage wheel for lateral movement relative to the axis of the workpiece into and out of contact with the threads thereof, means mounting said gage wheel on said pivotal means for rotation on and sliding along an axis parallel with the axis of rotation of said workpiece, an indicator on said pivoted means and having a member engaging the side of the gage wheel, said indicator being responsive through said member to the sliding movements of the gage wheel, and a second indicator adjacent and engaging said pivoted means thereby to indicate the lateral movements of the gage wheel.
3. In a machine for testing the threads of a threaded workpiece, means for supporting the workpiece for true rotation upon its axis, means for rotating the workpiece, a gage wheel having perfect threads thereon, the counterpart of which is desired in the workpiece threads, means for holding the gage wheel threads in close frictional contact with the threads of the workpiece, means mounting the gage wheel for longitudinal and lateral movement relative to the axis of the workpiece, and indicator means for indicating said movements of the gage wheel.
4. In a machine for gaging the external threads of a threaded workpiece for the detection of imperfections in the workpiece threads, a gage wheel having threads the exact counterpart of those desired in the workpiece and of the same pitch diameter and adapted to frictionally engage the threads of the workpiece, means for supporting the workpiece for true rotation upon its axis, means for rotating the workpiece, means mounting the gage wheel for longitudinal and lateral movement in parallelism with the workpiece

11

axis, and means for indicating such movements of the gage wheel.

5. In a machine for gaging the external threads of a threaded workpiece for the detection of imperfections in the workpiece threads, a gage wheel having perfect threads, the counterpart of which is desired in the workpiece, means mounting the gage wheel for longitudinal and lateral movement relative to the axis of the workpiece, means for indicating such movements, the threads on the workpiece and those on the gage wheel being opposite hand and of the same lead and pitch diameter so that when the threads are rolled in contact only imperfections in the workpiece threads will cause longitudinal or lateral movement of the gage wheel and consequent actuation of the indicator means.

6. In a machine for gaging the threads of an internally threaded workpiece, means for supporting the workpiece for true rotation on its axis, means for rotating the workpiece, a gage wheel having threads thereon the counterpart of which is desired in the workpiece threads, said gage wheel being smaller in diameter than the threaded opening of the workpiece and of the correct lead and pitch diameter of the workpiece threads and in engagement with said threads, means mounting said gage wheel for rotation and longitudinal and lateral movements, means for indicating the longitudinal and lateral movements of the gage wheel, and connections between said indicating means and the gage wheel whereby said means is operated to indicate such movements upon the rotation of the gage wheel.

7. In a machine for gaging the threads of an internally threaded workpiece, means for supporting the workpiece for true rotation on its axis, means for rotating the workpiece, a gage wheel having threads thereon the counterpart of which is desired in the workpiece, means mounting said gage wheel for rotation and longitudinal movements, said gage wheel being smaller in diameter than the threaded opening of the workpiece and having threads of the correct pitch diameter of the workpiece threads and in engagement with said threads whereby when the workpiece is rotated the gage wheel will be rotated and moved continuously longitudinally in a direction axially of the workpiece, a shaft rotatably supported in parallelism with the axes of the gage wheel and workpiece and provided with threads, a threaded sleeve engaging and moved by the threads of said shaft, connections between the workpiece rotating means and the shaft whereby the shaft is rotated in timed relation with the workpiece, connections between the sleeve on the shaft and the gage wheel constructed and arranged to subtract the axial movements of the gage wheel from the corresponding movement of the sleeve, and indicator means associated with said connections to indicate any difference in said movements.

8. In a machine for gaging the external threads of a threaded workpiece for the detection of imperfections in the workpiece threads, means for supporting the workpiece for true rotation upon its axis, means for rotating the workpiece, a rockable member adjacent the workpiece and movable to and from the workpiece, a shaft mounted in said member in parallelism with the axis of the workpiece, a gage wheel rotatable and slideable on said shaft and having perfect threads the counterpart of which is desired in the workpiece and adapted to engage the workpiece threads and rotatable thereby, said gage wheel

12

being provided with an elongated pinion, a gage member fast to the shaft, indicator means carried by the gage member and having a finger in engagement with the side of the gage wheel and moved thereby to indicate the longitudinal movements of the gage wheel, if any, an idler gear carried by the gage member and in gear with said pinion and rotated thereby, an electrical circuit including a magnet adapted when energized to urge the rockable member toward the threads of the workpiece, a switch in the circuit actuated by the idler wheel to open and close said circuit, and spring means arranged to urge the rockable member and gage wheel away from the workpiece when the magnet is de-energized.

9. In a machine for testing screw threads, means adapted to mount a workpiece for rotation about the axis of an internal thread of said workpiece, a hub having external threads of the same lead as said workpiece and a pitch diameter equal to a known fraction of the corresponding diameter of said workpiece thread, means mounting said hub for rotation on a second axis parallel to said first-named axis with said threads in engagement, a block translatable parallel with said axis, lever means pivoted on said block, a pivotal connection between one end of said lever means and said hub, means pivoting the other end of said lever means in timed relation with the rotation of said workpiece, and means measuring any translation of said block as a criterion of the lead of the threads of said workpiece.

10. In a machine for testing the threads of a threaded workpiece, means for supporting the workpiece for true rotation upon its axis, means operable to positively rotate the workpiece about its axis while so supported, a gage wheel having circumferentially complete perfect threads the counterpart of which is desired in the threads of the workpiece, means mounting said wheel to engage the workpiece threads in pure tangential rolling contact therewith, for axial translation and for lateral rocking movement toward and from the workpiece about an axis parallel with the axis of rotation thereof, and means responsive to axial translation and lateral rocking of said gage wheel to separately indicate such movements.

11. In a machine for gaging the threads of an internally threaded workpiece, means for supporting the workpiece for true rotation on its axis, power-driven means for rotating the workpiece, including a first gear having operative connections with the workpiece, a first shaft mounted for rotation in parallelism with the axis of the workpiece, a second gear on said shaft in mesh with said first gear whereby said shaft is rotated in timed relation with the workpiece, an arm rockably mounted on said first shaft, a second shaft carried by said arm, a third gear slideably and rotatably mounted on said second shaft and having an integral hub, a gage wheel fixed on said hub and having perfect threads the counterpart of which is desired in the threads of the workpiece, and adapted to engage said workpiece threads, a fourth gear fixed on said first shaft and in mesh with said third gear to drive the same, indicator means carried by said arm in position engaging the side of said third gear to indicate sliding movement of the gage wheel, and indicator means mounted adjacent and engaging said arm to indicate rocking movements thereof.

12. In a machine for testing the threads of a

workpiece having a first axis, said threads being supposedly co-axial with said axis, means mounting said workpiece for rotation only on said first axis, a shaft, means mounting said shaft in parallelism with and for movement toward and from said first axis, a gage wheel having perfect threads the counterpart of those required in said workpiece, said gage wheel being mounted for rotation and axial translation on said shaft, first gage means responsive to sliding of said gage wheel along said shaft, and second gage means responsive to change in separation of said first axis and the axis of said shaft.

FRANK SHORT.
